UNITED STATES PATENT OFFICE.

ROBERT A. ROSANDER, OF BROOKLYN, NEW YORK.

FURNACE.

1,320,276.

Specification of Letters Patent. Patented Oct. 28, 1919.

Original application filed July 16, 1918, Serial No. 245,195. Divided and this application filed October 23, 1918. Serial No. 259,401.

To all whom it may concern:

Be it known that I, ROBERT A. ROSANDER, a citizen of the United States, residing in the city of New York, borough of Brooklyn, 5 in the county of Kings and State of New York, have invented a certain new and useful Improvement in Furnaces, of which the following is a specification.

The present application is a division of an 10 application filed by me July 16, 1918, Serial No. 245,195.

The invention relates to house-heating plants, and the object of the invention is to provide a furnace in which the fuel may 15 be burned with but little loss of combustible gases, thereby effecting a corresponding economy in fuel-cost, and the elimination of objectionable smoke.

A further object is to provide means 20 whereby a portion of the grate surface may be economically employed alone when the full heating capacity of the furnace is not required.

Another important object is to provide a 25 furnace adapted to perform the dual function of supplying simultaneously both heated air for a hot-air heating system and hot water for a system in which hot water is employed as the heating medium, or for 30 other purposes requiring a supply of hot water.

A further important object is to provide means for controlling the flow of the hot 35 products of combustion to the smoke-flue and through the radiator sections, and for insuring efficient radiation to the air to be heated.

The invention consists in certain novel 40 features of construction and arrangement by which the above objects are attained, to be hereinafter described and claimed.

The accompanying drawings form a part 45 of this specification, and show an approved form of the invention.

Figure 1 is a central vertical section 50 through the furnace, taken longitudinally of the grates, and partly in elevation.

Fig. 2 is a similar view taken transversely of the grates.

Fig. 3 is a horizontal section and plan 55 view, taken on the line 3-3 in Fig. 2.

Fig. 4 is a vertical longitudinal section corresponding to a portion of Fig. 1, but on a larger scale, and partly in elevation.

Fig. 5 is a transverse section taken on the 55 line 5-5 in the preceding figure.

Similar letters of reference indicate the same parts in all the figures.

A is the base of the furnace, equipped 60 with ash-pit doors A¹ each having an adjustable air-inlet opening A²; this casting is preferably rectangular in plan, and the parts above may be understood to have the same general form. An inwardly projecting ledge A³ on the base supports a frame B 65 having in each side an opening b for the horizontally disposed grates C, and a central opening in which is received the lower header D² of a combustion compartment having an upper header D¹ and connecting 70 water tubes D, as will be described. The frame B and grates C form the floor of the fire-space or fire-pot.

Mounted upon the base A is a vertical 75 shell F having on its sides oppositely located fire-doors F¹ at the upper end and similarly placed air-doors F² at the lower end immediately above the grates C.

Within the shell F and extending from the grates to the fire-doors is a heavy lining- 80 casting E having its lower margins deeply notched or serrated to form fingers E¹ and serving as a fire-pot to inclose the burning fuel and admit air thereto between the fingers.

The combustion compartment extends the 85 full length of the grates C from one side of the lining E to the other, thus dividing the fire-pot into two portions, and stands between the grates. The headers D¹ D² are 90 hollow and rectangular in plan and each has a vertically arranged aperture or flue d¹ d². The vertical tubes D connecting the headers are located in alinement to form four open-work walls, each tube separated from the 95 next by a narrow space d of such width as to exclude the fuel but permit the gases therefrom to enter the combustion compartment inclosed by the rectangularly arranged four rows of tubes.

Rotatably mounted below the lower header and extending centrally of the opening or aperture d² therein, is a bar G having its end protruding through the base and shaped to receive a wrench or other shaking implement by which it may be rotated. The bar carries three equally spaced longitudinally extending radial wings G¹, shown as cast in-

tegrally with the bar, thus presenting a triangular cross-section with concave faces. The wings are of such length and so located relatively to the aperture d^2 as to close the latter completely in one position, as indicated in full lines in Fig. 5, thus practically shutting off the flow of air to the combustion compartment from the ash-pit, and when rotated through an arc of 60° permits a practically unobstructed flow of air to the interior of the combustion compartment from below the grates, as shown by dotted lines in Fig. 5, thus permitting the supply of air from this source to be varied or regulated as required. By rotating this winged bar any fine dust or ashes thereon, accumulated in the compartment may be dumped into the ash-pit.

The system of headers and water-tubes forming the combustion compartment is supported on laterally extending ridges E^2 on the inner faces of the fire-pot or lining E , shaped as pockets to receive the ends of the upper header D^1 and thus hold the compartment suspended.

Upon the upper header D^1 is a hollow casting H forming a chamber in which the hot products of combustion from the combustion compartment are delivered. It is preferably lined with fire-brick H^1 to withstand the impact of the hot current and protect the metal. The casting H has on one side a nipple H^2 extending horizontally through the shell F , which receives a branch smoke-pipe H^3 having a vertical portion or flue H^6 provided with a wing-damper H^4 , and on the other side of the casting is an opening h leading to a vertical pipe or flue H^6 extending through a horizontal plate F^3 forming the cover or top of the shell F .

A rim F^4 on the cover F^3 supports a sheet-metal casing J serving as an air chamber from which extend the hot-air conduits J^1 leading to the several rooms or apartments in the building as usual. The casing J contains a series of hollow radiator sections K^1 K^2 K^3 mounted one above the other, the lowermost K^1 having a nipple at one side in the bottom, matching to the flue H^6 , and a nipple on the other side, on the upper face, in communication with the interior of the second section K^2 which in turn is similarly joined to the third or uppermost section K^3 which has an opening k on one side face receiving a smoke-pipe K leading to a chimney, not shown, and of which the pipe H^5 is a branch. Beyond the junction with the branch is a damper K^4 by which the draft to the chimney may be controlled and regulated. The radiator sections are provided with studs K^6 serving as supports.

The grates C are mounted above the openings b in the frame B with provisions for dumping by means of the bars C^1 extending to the exterior of the base, and the doors F^2

at the bottom of the shell F are provided with air inlet openings and means for controlling the flow of air therethrough to the fire-pot.

From the ends of the headers D^1 D^2 extend oppositely located water pipes D^3 D^4 through which water contained in the headers and water tubes D may be circulated in supplying a hot-water heating system, or other service, as will be understood.

The operation of the improved furnace is as follows:

Fire is built on the grates, and coal which may be pea or other small size, is supplied through the fire-doors F^1 until the sides of the combustion compartment are inclosed. The dampers H^4 and K^4 are both opened to permit the smoke to pass directly to the chimney through the branch H^3 until the lower portion or layer of the coal supply is ignited and glowing under the draft from the interior of the combustion compartment, the air currents thus induced entering mainly through the grates C from the ash-pit. When the fire is thus sufficiently advanced, the admission of air below the grates is checked, and the openings in the air-doors F^2 uncovered to permit air to pass between the fingers of the fire-pot on both sides, through the mass of heated coal in and immediately above the fire-layer, to and between the water-tubes D to the interior of the combustion compartment, carrying with it the unburned combustible gases from the heated coal intimately mingled with such air at a temperature at which the carbon gases will combine with the oxygen and burn with practically perfect combustion, producing an intense heat in the interior of the combustion compartment.

The damper H^4 is then closed and the hot products of combustion compelled to traverse the radiator sections K^1 K^2 K^3 thus transferring a large proportion of their intense heat to the air entering the casing J through the perforations J^2 in its lower portion, and escaping through the hot-air conduits J^1 to the registers throughout the building. The form of the radiator sections is preferably rectangular so as to present a large radiating surface to the air to be warmed.

Air entering the ash-pit becomes warmed by the downward radiation from the grates and adjacent hot surfaces and may be admitted as required through the opening d^2 in case a larger proportion of oxygen is necessary than is received through the mass of coal. By manipulating the damper or bar G^1 and the controlling means on the air-doors F^2 the proportion of air relatively to the gases supplied to the combustion compartment may be varied and regulated very exactly and perfect combustion closely approximated.

The water circulated through the headers D¹ D² and water-tubes D serves to lower the temperature of the compartment walls and condition the latter to resist successfully the intense heat to which they are subjected, and the heat thus transferred to the water may be utilized in a hot-water plant for house heating or serve as a hot water supply for domestic or other purposes.

10 It has been demonstrated by experiment that a comparatively small quantity of coal is required, that the waste in unburned fuel is materially reduced, and very little heat lost by radiation from the exterior of the 15 furnace, and also that the fire tends to remain in a shallow layer upon the grates, replenished automatically from the mass above. Inferior grades of anthracite and bituminous coal may be used successfully and with- 20 out smoke.

When less heat is required, as in periods of mild weather, only one side of the fire-pot need be used, the operation being as before but with a corresponding reduction of heat 25 and of fuel.

The size of the tubes D and the width of intervening spaces are carefully calculated to permit the required flow of air and hot gases to the combustion compartment; the 30 proportions shown in the drawings are approximately correct for successful operation.

I claim:—

1. In a furnace, a base, a casing mounted 35 on said base and having a closed top, a fire-pot in said casing depending from said closed top, a closure having an open bottom and

located in the upper end of said fire-pot, said closure having a lateral nipple extending through said fire-pot and casing for the 40 escape of the products of combustion, and a vertical nipple projecting through the top of said casing, a series of radiator sections located above the top of said casing, a smoke flue connected with the uppermost 45 radiator section, a branch smoke flue connected at one end with said lateral nipple and at the other end with said smoke pipe, a casing surrounding said radiator sections, and hot air pipes leading from said casing. 50

2. In a furnace, a base, a casing mounted on said base and having a closed top, a fire-pot in said casing depending from said closed top, a closure having an open bottom and located in the upper end of said fire-pot, 55 said closure having a lateral nipple extending through said fire-pot and casing for the escape of the products of combustion, and a vertical nipple projecting through the top of said casing, a series of radiator sections 60 located above the top of said casing, a smoke flue connected with the uppermost radiator section, a branch smoke flue connected at one end with said lateral nipple and at the other end with said smoke pipe, a 65 casing surrounding said radiator sections, and hot air pipes leading from said casing, the said casing being provided at its lower portion with perforations for the ingress of air to said casing. 70

In testimony that I claim the invention above set forth I affix my signature.

ROBERT A. ROSANDER.
